UNITED STATES PATENT OFFICE

2,582,766

VENDING MACHINE

Henry A. Burggrabe, Detroit, Mich., assignor to
 F. L. Jacobs Co., Detroit, Mich., a corporation
 of Michigan

Application July 22, 1948, Serial No. 40,183

14 Claims. (Cl. 312—97.1)

1 The present invention relates to vending machines and more particularly to an improved coin-operated vending machine adapted to be operated by the purchasing public and to automatically deliver the vended articles.

In vending machines of the above mentioned type, it is important that the construction of the machine be such that members of the public who are so inclined may not remove from the machine the articles to be vended without deposit of the required coins. It is equally important that the construction of the machines be such that coins deposited in the machine will be returned in the event that the machine cannot deliver one of the articles to be vended.

Accordingly, it is an object of the present invention to provide a vending machine having an improved construction preventing the removal of the articles to be vended from the machine by members of the purchasing public other than by the deposit of the proper coin in the machine.

Another object of the invention is to provide an improved vending machine of the above mentioned type having a delivery chute and a shutter normally locked in a closed position except during a vending operation of the machine, during which it is moved to an open position simultaneously with the delivery of a vended article through the delivery chute.

Another object of the invention is to provide an improved vending machine including means for automatically shutting off the machine upon the normal delivery of a vended article, and other means effective upon the partial or faulty delivery of a vended article, such as may be caused by one tampering with the machine, or otherwise, to automatically shut off the machine and prevent its becoming jammed.

A further object of the present invention is to provide an improved vending machine including an electric motor having a thermal responsive circuit-controlling means adapted to open the circuit to the motor when the latter becomes overheated, and a coin selector mechanism, including an electromagnet adapted when energized to permit a coin to be selected for actuating the machine, and in which the thermal responsive circuit-controlling means is connected in series with the electromagnet preventing the latter from being energized when the circuit to the motor is broken by the thermal responsive circuit-controlling means.

It is also an object of the invention to provide an improved vending machine having improved driving means for indexing the means supporting the articles to be vended, which driving means is of a construction affording a mechanical lock preventing indexing of the article-supporting means by directly engaging the latter, as is frequently attempted in this type of vending ma-

2 chine by one seeking to steal the articles from the machines.

Other and more detailed objects of the invention will become apparent from a consideration of the following specification, the appended claims and the accompanying drawings, throughout the several views of which like reference characters designate like parts, and wherein:

Fig. 1 is an elevational view of a vending machine embodying the present invention, showing the loading door in its open position;

Fig. 2 is a front elevation of the construction illustrated in Fig. 1;

Fig. 3 is an enlarged broken sectional view of the construction illustrated in Fig. 1, taken substantially along the line 3—3 thereof;

Figs. 4 and 5 are broken sectional views of the construction illustrated in Fig. 3 taken substantially along the lines 4—4 and 5—5 thereof, respectively;

Fig. 6 is an enlarged broken sectional view of the construction illustrated in Fig. 2 taken substantially along the line 6—6 thereof;

Fig. 7 is a broken sectional view of the construction illustrated in Fig. 5 taken substantially along the line 7—7 thereof;

Fig. 8 is an enlarged broken sectional view similar to Fig. 4 illustrating a position assumed by the various parts during delivery of a vended article; and

Fig. 9 is a schematic wiring diagram showing only the circuit interconnecting the thermal responsive circuit-controlling means associated with the motor and the electromagnet of the coin selector mechanism which must be energized prior to the selection of a coin by the mechanism.

It will be appreciated by those skilled in the art that improvements of the present invention may be readily incorporated in vending machines of widely differing types and constructions. In an illustrative but not in a limiting sense, the improvements of the present invention are herein illustrated and described in connection with a bottle-dispensing machine of the type commonly employed in the vending of soft drinks.

Referring to the drawings, the vending machine of the present invention generally comprises a cabinet 20 having an upper loading door 22 and a lower access door 24, suitable refrigeration equipment mounted in the lower portion of the cabinet 20 (not shown), a drum housing 26 mounted in the upper portion of the cabinet in a conventional inclined position best illustrated in Fig. 2, and supporting a partitioned drum 28 adapted to carry the bottles to be vended and a motor 30 drivingly connected to the drum 28 as hereinafter described for indexing the latter between a plurality of vending positions, and providing a delivery chute 32 (see Fig. 4) through which vended articles are delivered from the drum

28, and a coin selector mechanism 34 mounted on the cabinet 20 and adapted to control the operation of the motor 30 for indexing the drum 28.

In spaced relation to the coin selector mechanism 34 the cabinet 20 has a bottle delivery station 36 where a vended bottle is received from the delivery chute 32 of the drum housing 26 and delivered to the outside of the cabinet 20 through a door 38 which is pivotally mounted and yieldably held in a normally closed position. The lower portion of the cabinet 20 houses suitable refrigeration equipment (not shown) for maintaining the interior of the cabinet at a predetermined desired temperature, and may also in part serve as a storage area for precooling bottles which may be later loaded into the drum 28 and vended by the machine.

The drum 28 is of the partitioned construction usual in bottle-vending machines of this type and carries a centrally disposed ring gear 40 secured to its outer periphery. As best illustrated in Fig. 6, the ring gear 40 is driven by a pinion 42 which is connected to a worm gear 44 for rotation therewith. The gear 44 is driven by a worm 46 connected to the output shaft of the motor 30. The worm 46 and the worm gear 44 are of a conventional design in which the gear 44 may be readily driven by the worm 46 but the reverse is not true and the worm 46 may not be driven by the worm gear 44. Accordingly it will be appreciated that the above described drive mechanism affords a mechanical lock preventing rotation of the drum 28 by directly engaging the drum manually or otherwise.

At its inner or right-hand end, as viewed in Figs. 2 and 3, the drum 28 is provided with an axially extending flange 48 having a plurality of equally spaced notches 50 individual to and corresponding to the drum spaces defined by the partitions 52 thereof.

An inner door or shutter 54, normally closing the delivery chute 32, is slidably mounted on a pair of spaced brackets 56 secured to the drum housing 26 for sliding movement between the normally closed position illustrated in Figs. 3, 4, 5 and 7, in which it closes the delivery chute 32, and the raised or open position illustrated in Fig. 8, in which a vended bottle may pass through the delivery chute 32. The spaced guide plates 56 are disposed on opposite sides of the delivery chute 32 and have outwardly turned flanges 58 which are welded or otherwise suitably secured to the drum housing 26. The inner edges of the guide brackets 56 are disposed on parallel arcs about centers lying in the axis of the drum 28 and terminate in outwardly extending guide flanges 60 which are received within reversely turned side portions 62 of the shutter 54 to slidably mount the latter on the guide brackets 56.

For raising the shutter 54 from the above described closed position to the raised or open position illustrated in Fig. 8, a latch arm 64 is pivotally mounted intermediate its ends on a pivot pin 66 mounted on the shutter 54 and extending parallel to the axis of the drum 28 and laterally outwardly from one side of the shutter 54. The disposition of the shutter 54 relative to the flange 48 on the drum 28 is such that the latch arm 64 is disposed in a plane passing through the slots 50 formed in the flange 48. The latch arm 64 is provided with a hook portion 68 at its inner end adapted to move into and out of the notches or slots 50 upon pivotal movement of the latch arm 64. The latch arm 64 is provided with a spring 70 urging the latch arm

64 to pivot in a clockwise direction about the pivot pin 66 (as viewed in Fig. 4) which serves to urge the hook portion 68 of the latch arm 64 against the drum 28 and into the slots 50 provided therein.

It will now be appreciated that when the drum 28, which travels in a clockwise direction as viewed in Fig. 4, is driven by the motor 30, the shutter 54 will be raised through its connection to the drum 28 by the latch arm 64. As the drum 28 approaches the end of each indexing movement, the latch 64 is pivoted in a counterclockwise direction as viewed in Fig. 4 and the hook portion 68 thereof is withdrawn from the slot 50 in the drum 28. This movement of the latch arm 64 is effected by a stop member 72 fixed on a wire 74 which extends through an element 76 pivotally mounted on the latch arm 64 at the opposite end thereof with relation to the hook portion 68. The element 76 is adapted to slide along the wire 74 during the upward movement of the shutter 54 and to engage the stop member 72 at the upper end of the wire 74 whereby continued upward movement of the shutter 54 effects the above mentioned counterclockwise movement of the latch arm 64 and withdraws the hook portion 68 thereof from the slot 50 of the drum 28. If at this time the delivery chute 32 is unobstructed, the force of gravity acting on the shutter 54 will cause it and the latch arm 64 carried thereby to return to their closed position, it being further appreciated that as the latch arm 64 approaches this normally closed position the spring 70 acting thereon urges the hook portion 68 thereof into the next slot 50.

To insure that this counterclockwise pivotal movement of the latch arm 64 occurs at the proper time, an abutment 73 is fixed to the cabinet 20, as illustrated in Figures 4 and 8, in position to engage the latch arm 64 below the pivot pin 66 and effect such movement. If desired, this movement may be effected entirely by the stop 73 and the stop 72 employed only as herein-after described in loading the drum 28.

The construction of the machine and the proportioning of the various parts thereof are such that during an indexing movement of the drum 28 and substantially at the same time as the hook portion 68 of the latch arm 64 is released from the drum 28, but slightly prior thereto, a vended bottle is discharged from the adjacent partitioned sector of the drum 28 as it moves into alignment with the delivery chute 32. As this vended bottle moves into the delivery chute it trips a shut-off mechanism generally indicated at 78 which stops the motor 30 after the hook portion 68 of the latch arm 64 is withdrawn from the notch 50 of the drum. This shut-off mechanism 78 is mounted on the underside of the chute 32 and projects upwardly into the chute 32 through an aperture 80 therein.

The shut-off mechanism 78 comprises a stationary bracket 82 secured to the underside of the delivery chute 32 adjacent the aperture 80 by a pair of screws 84 and having a pair of spaced downwardly projecting tabs 86 which support a pivot pin 88 disposed at right angles to the delivery chute 32. A trip lever 89 is pivotally mounted on the pivot pin 88 and projects upwardly through the aperture 80 into the delivery chute 32. This trip lever 89 is adapted to be engaged by a vended bottle as it passes through the delivery chute 32 and to be pivoted thereby from the upright position illustrated in Fig. 5

to the tripped position illustrated in Fig. 8. A mercury switch 90 is secured to a supporting bracket 92 which is also pivotally mounted on the pivot pin 88 and has an upwardly extending arm 94 which is normally held in engagement with the outer surface of the trip lever 89 by a spring 96 which encircles the pivot pin 88 and one end of which engages the arm 94 and the other end of which engages the stationary bracket 82. The trip lever 89 has an arcuately extending channel-shaped portion 98 which encloses the arm 94 of the mercury switch supporting bracket 92 while permitting pivotal movement of the bracket 92 independently of movement of the trip lever 89.

It will be appreciated that the spring 96 through its engagement with the arm 94 of the switch bracket 92 and the engagement of the latter with the trip lever 89 acts to normally maintain the trip lever 89 in the upright position illustrated in Figs. 4, 5 and 7. It will also be appreciated that when the trip lever 89 is pivoted to the position illustrated in Fig. 8 by a vended bottle passing through the delivery chute 32, it will, through its engagement with the arm 94, pivot the switch supporting bracket 92 and the mercury switch 90 to the position best illustrated in Fig. 8 in which the circuit through the switch is broken. This switch 90 is connected in series with the electric motor 30 and, accordingly, pivotal movement of it to the position illustrated in Fig. 8 results in breaking the circuit to the motor 30 and stopping the latter.

It is an important feature of the present invention that the motor 30 will be stopped and consequent jamming of the machine avoided even though there is a faulty delivery of the vended bottle and the tripping lever 89 is not tripped. For effecting a stopping of the machine in such an eventuality, a wire 100 is provided having its lower end pivotally connected to the switch bracket 92 and having a stop 102 secured to its upper end and adapted to be engaged by an element 104 secured to and movable with the shutter 54 and which receives the wire 100 and slides therealong during movement of the shutter 54.

It will now be appreciated that if a vended bottle remains in the delivery chute 32 above the tripping lever 89, the shutter 54 will be unable to close when the latch arm 64 is disengaged from the drum 28 and continued movement of the drum will force the partially vended bottle upwardly against the shutter 54 which, acting through the engagement of the element 104 with the stop member 102 on the wire 100, will pivot the switch supporting bracket 92 and the mercury switch 90 to the position illustrated in Fig. 8 in which the circuit through the switch 90 is broken. It will also be noted that by virtue of the above described construction this pivotal movement of the switch supporting bracket 92 and the switch 90 will be effected independently of whether the tripping lever 89 is held in the upright position illustrated in Figs. 4 and 5 or is permitted to drop to the tripped position illustrated in Fig. 8.

As is usual in machines of this type, the electrical system of the machine is such that once the operating circuit is broken, as by the tripping of the switch 90, the motor 30 may not be restarted without the insertion of another coin, and the operating circuit to the motor 30 is not reestablished by the switch 90 returning to its closed position, as after the vended bottle passes

from the machine. The machine also includes the usual bottle support and switch mechanism generally indicated at 106 for preventing operation of the machine when empty, and the usual separator plate 108 for preventing bottles in addition to the vended bottle from being removed from the drum 28.

To facilitate the loading of a drum 28 by one servicing the machine, means are provided for disengaging the latch arm 64 from the drum 28 during the loading operation. For this purpose, the above mentioned wire 74 carrying the stop 72 and passing through the element 76 on the latch arm 64 extends through a supporting tube 110 and is connected to a loading lever 112 mounted on the drum housing 26 and accessible to the attendant upon opening the cabinet door 22. By operation of the loading lever 112, the wire 74 may be pulled to a position in which the stop 72 engages the element 76 and pivots the latch arm 64 to a retracted position in which it is clear of the drum 28. When the loading lever 112 is locked in this position, the motor 30 may be operated by suitable switch means (not shown) accessible to the attendant within the cabinet 29 to index the drum 28 as desired during the loading operation.

As a further device for preventing the unauthorized removal of bottles from the drum 28, the machine includes a plate 118 supported on a suitable frame 120 detachably mounted on the drum housing 26 at the end of the drum 28 adjacent the cabinet door 22 and closely covering the end of the drum partition space aligned with the delivery chute 32 to prevent a prospective thief from reaching through the delivery chute 32 and the aligned drum partition space and removing bottles from adjacent partition spaces of the drum. A semicircular ring 122 is supported on the bracket 120 and disposed closely adjacent the ends of the upper drum partition spaces to prevent bottles in these partition spaces from falling out. During loading, the attendant may remove the frame 120 to facilitate access to the drum partition spaces.

Referring to Fig. 9, the electric motor 30 is provided with a conventional thermal-responsive circuit breaking mechanism 129 for preventing overheating of the motor, and the above mentioned coin selector mechanism 34 (see Fig. 1) includes an electromagnet 130 which when energized moves a pivotally mounted arm 132 forming a part of the coin selector mechanism and adapted to prevent selection of a coin by the mechanism in the absence of a suitable power supply to the machine. As illustrated in the partial wiring diagram shown in Fig. 9, the thermal protector 129 of the motor 30 is connected in series with the electromagnet 130 between the power supply lines 134 and 136, thereby insuring that the circuit to the latter will be broken when the circuit through the thermal protector 129 is broken and preventing the acceptance of a coin when the motor is overheated. The remainder of the wiring diagram may be in accordance with conventional practice.

While only one specific embodiment of the invention has been illustrated and described in detail herein, it will be readily appreciated by those skilled in the art that numerous modifications and changes may be made without departing from the spirit and scope of the invention.

What is claimed is:

1. A vending machine comprising means for

supporting the articles to be vended, said means being movable in one direction to facilitate loading thereof with articles to be vended, a delivery chute, means operable to move said means in said one direction, index said means and deliver a vended article through said delivery chute, a shutter operable to open and close said chute, means mounted on said shutter and engaged by said first named means to move said shutter to open said chute, said last named means normally engaging said first named means, between operations of the latter, to hold said shutter in position to close said chute, and means for withdrawing said last named means from engagement with said first named means to prevent interference of said last named means with said first named means during movement thereof while loading said first named means with articles to be vended.

2. A vending machine comprising means for supporting the articles to be vended, said means being movable in one direction to facilitate loading thereof with articles to be vended, a delivery chute, means operable to move said means in said one direction, index said means and deliver a vended article through said delivery chute, a shutter operable to open and close said chute, means mounted on said shutter and engaged by said first named means to move said shutter to open said chute, said last named means normally engaging said first named means, between operations of the latter, to hold said shutter in position to close said chute, and means for withdrawing said last named means from engagement with said first named means and holding the former out of engagement with the latter to prevent interference of said last named means with said first named means during movement thereof while loading said first named means with articles to be vended.

3. A vending machine comprising a rotatably mounted drum adapted to carry articles to be vended and having notches adjacent its periphery, a delivery chute for conveying vended articles to the outside of said machine, means for indexing said drum and discharging a vended article from said drum into said delivery chute, a shutter disposed in and normally closing said chute, a latch mounted on said shutter and normally engaging said drum at one of said notches, and means effective in response to an indexing of said drum for withdrawing said latch from said one of said notches.

4. A vending machine comprising a rotatably mounted drum adapted to carry articles to be vended and having notches adjacent its periphery, a delivery chute for conveying vended articles to the outside of said machine, means for indexing said drum and discharging a vended article from said drum into said delivery chute, a shutter disposed in and normally closing said chute, a latch mounted on said shutter and normally engaging said drum at one of said notches, and means effective in response to an indexing of said drum for disengaging said latch from one of said notches and engaging said latch in another of said notches.

5. A vending machine comprising a rotatably mounted drum adapted to carry articles to be vended and having notches adjacent its periphery, a delivery chute for conveying vended articles to the outside of said machine, means for indexing said drum and discharging a vended article from said drum into said delivery chute, a shutter disposed in and normally closing said

chute and a latch mounted on said shutter and normally engaging said drum at one of said notches, whereby upon an indexing movement of said drum said shutter is moved to open said chute simultaneously with the delivery of a vended article through said delivery chute.

6. A vending machine comprising a rotatably mounted drum adapted to carry articles to be vended and having notches adjacent its periphery, a delivery chute for conveying vended articles to the outside of said machine, means for indexing said drum and discharging a vended article from said drum into said delivery chute, a shutter disposed in and normally closing said chute, and a latch mounted on said shutter and normally engaging said drum at one of said notches, whereby upon indexing movement of said drum said shutter is moved to open said chute simultaneously with the delivery of a vended article through said delivery chute, said latch being effective, when received in one of said notches, for preventing movement of said shutter relative to said drum.

7. A vending machine comprising a rotatably mounted drum adapted to carry articles to be vended and having notches adjacent its periphery, a delivery chute for conveying vended articles to the outside of said machine, means for indexing said drum and discharging a vended article from said drum into said delivery chute, a shutter disposed in and normally closing said chute, a latch mounted on said shutter and normally engaging said drum at one of said notches, whereby upon an indexing movement of said drum said shutter is moved to open said chute simultaneously with the delivery of a vended article through said delivery chute, said latch being effective, when received in one of said notches, for preventing movement of said shutter relative to said drum, and said first named means being so constructed and arranged as to prevent rotation of said drum by directly engaging the latter.

8. A vending machine comprising a rotatably mounted drum adapted to carry articles to be vended and having notches adjacent its periphery, a delivery chute for conveying vended articles to the outside of said machine, means for indexing said drum and discharging a vended article from said drum into said delivery chute, a shutter disposed in and normally closing said chute, a latch mounted on said shutter and normally engaging said drum at one of said notches, whereby upon an indexing movement of said drum said shutter is moved to open said chute simultaneously with the delivery of a vended article through said delivery chute, said latch being effective, when received in one of said notches, for preventing movement of said shutter relative to said drum, and means effective upon completion of an indexing movement of said drum for disengaging said latch from one of said notches and engaging said latch in another of said notches.

9. A vending machine comprising a rotatably mounted drum adapted to carry articles to be vended and having notches adjacent its periphery, a delivery chute for conveying vended articles to the outside of said machine, means for indexing said drum and discharging a vended article from said drum into said delivery chute, a shutter disposed in and normally closing said chute, a latch pivotally mounted on said shutter and normally engaging said drum at one of said notches, and means effective in response to an

indexing of said drum for withdrawing said latch from said one of said notches, said last named means comprising stop means adapted to engage said latch on the opposite side of its pivotal connection to said shutter from its engagement with said drum as the latter completes an indexing movement, to pivotally move said latch in a direction to withdraw it from said one of said notches.

10. A vending machine comprising a rotatably mounted drum adapted to carry articles to be vended and having notches adjacent its periphery, a delivery chute for conveying vended articles to the outside of said machine, means for indexing said drum and discharging a vended article from said drum into said delivery chute, a shutter disposed in and normally closing said chute, a latch pivotally mounted on said shutter and normally engaging said drum at one of said notches, and means effective in response to an indexing of said drum for moving said latch to another of said notches, said last named means comprising stop means adapted to engage said latch on the opposite side of its pivotal connection to said shutter from its engagement with said drum as the latter completes an indexing movement, to pivotally move said latch in a direction to withdraw it from said one of said notches, means for guiding said shutter to its normally closed position and spring means yieldably urging said latch to pivotally move in the opposite direction.

11. A vending machine comprising a rotatably mounted drum adapted to carry articles to be vended and having notches adjacent its periphery, a delivery chute for conveying vended articles to the outside of said machine, means including electric drive means for indexing said drum and discharging a vended article from said drum into said delivery chute, a shutter disposed in and normally closing said chute, a latch mounted on said shutter and normally engaging said drum at one of said notches, a bracket pivotally mounted on said machine, electric switch means mounted on said bracket adapted to control said drive means, and to be actuated by pivotal movement of said bracket, and means operatively connecting said bracket and shutter whereby movement of said shutter beyond its normal travel during an indexing movement, will pivotally move said bracket to actuate said switch means and stop said drive means to prevent jamming of said machine.

12. A vending machine comprising a rotatably mounted drum adapted to carry articles to be vended and having notches adjacent its periphery, a delivery chute for conveying vended articles to the outside of said machine, means including electric drive means for indexing said drum and discharging a vended article from said drum into said delivery chute, a shutter disposed in and normally closing said chute, a latch mounted on said shutter and normally engaging said drum at one of said notches, a bracket pivotally mounted on said machine, electric switch means mounted on said bracket adapted to con-

trol said drive means, and to be actuated by pivotal movement of said bracket, a trip adapted to be actuated by a vended article delivered through said chute and effective to pivotally move said bracket to actuate said switch means, and means operatively connecting said bracket and shutter whereby movement of said shutter beyond its normal travel during an indexing movement, will pivotally move said bracket to actuate said switch means and stop said drive means to prevent jamming of said machine.

13. A control mechanism for a vending machine having a drum adapted to carry articles to be vended, means including electric drive means for indexing said drum and delivering vended articles from said machine, and a shutter movable between a normally closed position and an open position to which it is moved in normal delivery of vended articles, said control mechanism comprising a normally closed electric switch adapted to control the electric circuit to said electric drive means, means adapted to be actuated by a vended article in the normal delivery thereof to open said switch and stop said electric drive means, and means adapted to be actuated by a partially delivered article, upon continued movement of said drum to effect movement of said shutter beyond said open position and open said switch to stop said electric drive means.

14. A control mechanism for a vending machine having a drum adapted to carry articles to be vended and means including electric drive means for indexing said drum and delivering vended articles from said machine, said control mechanism comprising a normally closed electric switch adapted to control the electric circuit to said electric drive means, means adapted to be actuated by a normally delivered vended article to open said switch and stop said electric drive means, and means adapted to be actuated by a partially delivered vended article which is ineffective to actuate said last named means upon continued movement of said drum, to open said switch and stop said electric drive means.
